UNITED STATES PATENT OFFICE.

EDWIN A. MCKOY AND GEORGE D. MOORE, OF NEW ORLEANS, LOUISIANA.

SHORTENED CONICAL CUTTER HEAD.

Application filed May 23, 1921, Serial No. 471,626. Renewed July 16, 1923.

To all whom it may concern:

Be it known that we, EDWIN A. MCKOY and GEORGE D. MOORE, citizens of the United States, residing at New Orleans, in the parish of Orleans and State of Louisiana, have invented certain new and useful Improvements in Shortened Conical Cutter Heads, of which the following is a specification.

This invention relates to shortened conical cutter heads, and has for an object to provide a cutter head generally conical in shape but with the apex truncated or reversed as an inwardly extending cone whereby the travel of the cutter head is shortened in moving from the start to the finish of its work.

A further object of the invention is to shorten a conical cutter head by the provision of a point inset within an inwardly extending conical cavity whereby the cutter head first engages the work upon a circle substantially concentric with the engagement of the centering point.

A further object of the invention is to provide a cutter head having conical sides truncated to a predetermined distance from what would be the apex, from the circular edge of the plane of truncation an inwardly extending conical cavity is formed with a centering bit centrally located within such cavity and extending along the axis of rotation of the head, the point of such bit terminating substantially in the plane of said circular edge.

With these and other objects in view, the device comprises certain novel parts, units, elements, combinations, arrangements and functions, as will be hereinafter more fully described and claimed.

In the drawings:

Figure 1 is a view of the device partly in side elevation and partly broken away, showing the relation of the cutting point to the conical sides of the head.

Figure 2 is a view in inverted plan of the improved head.

Like characters of reference indicate corresponding parts throughout the several views.

In the use of cutter heads, especially cutter heads intended for the cutting or disintegration of standing stumps, it is found desirable to make the head generally conical in form, with the sides inclined approximately 45° to the axis. This arrangement and inclination is found desirable because

of the action of the cutter head upon the wood and resistance of the wood to the cutting.

In the use of larger cutter heads for disintegrating large stumps, the angle of 45° produces a cutter head of considerable length requiring an undesirable lift of the device to engage the top of a stump, so that the point of the cutting head will clear the stump when the device is being set.

The present invention is, therefore, directed to eliminating a part of the vertical dimensions of a cutter head, and still retain the desired angle approximately 45°, it being understood, however, that the particular angle is not essential to the present invention.

To accomplish this, the body of the device is formed generally conical, as indicated at 10, and the angle as shown in the drawings is approximately 45° to the axis, but as above noted, this particular angle, while desirable, is not essential.

Instead of continuing the body to an apex 80 of a complete cone, the cone is truncated at 11 by forming a re-entrant conical portion 12, with a centering bit 13 centrally located within this re-entrant cone with its point 14 preferably substantially in the plane of truncation defined by the line 11.

The conical cutter head is provided with cutting knives, which may be of any type and mounted in any approved manner, one manner being shown as embodying a plurality of slots 15 through the body of the head which is made hollow, arranging such slots in staggered relation, and setting knives 16 in such slots with their cutting edges projecting beyond the conical surface of the body. The knives are secured in any approved manner, as by the bolts 17.

At the plane of truncation indicated by the edge 11, a second or reversely inclined knife 18 is employed, the lower cutting corner of which coincides substantially with the lower cutting corner of the innermost knives 16. The inner ends of the knives 18 extend to, and are protected by the shoulder 13' of the centering bit 13, whereby when the device is lowered upon the top of a stump as indicated conventionally at Figure 1, the corners of the knives 16 and 18 will rotate about the point 14 of the centering bit 13 and cut a circular trough which becomes tapered in both directions from the line of initial engagement as the cutter head is ad-

vanced as an entirety upon its axis of rotation. When the cutter head has advanced to an extent equal the space between the centering point 14 and the top of the shoulder 13', an annular rib will be formed, inclined in opposite directions to the central point 14 of the bit 13 at one side, and the line 11 at the opposite side. As the head advances still more, the stump will be disintegrated, 10 the shape of the cut forming to the outline of the head, forming an inwardly inclined conical cavity, at the bottom of which is an up-standing annular rib inclined to a point in the middle and exteriorly to the sides of the 15 conical cavity. When the cutting of the stump has been completed, the head is lifted, and by reason of the insetting of the point the lift is less in a device constructed in accordance with the present invention 20 than it is when the point continues to an apex.

We claim:

1. A cutter head comprising a conical body truncated and formed with a cavity 25 within the perimeter of truncation, and cutters carried by the head conforming substantially to the lines of the cone and the cavity.
2. A cutter head substantially conical and truncated, having a conical cavity inset from 30 the plane of truncation, and cutters carried by, and coinciding substantially with the conical sides of the head and the cavity.
3. A cutter head comprising a substantially conical body truncated and having a 35 substantially conical cavity extending inwardly from the plane of truncation, a centering bit disposed within the cavity, and cutters carried by, and co-inciding substantially with the walls of the body and cavity.
4. A cutter head comprising a substantially conical body truncated and having a 40

substantially conical cavity extending inwardly from the plane of truncation, a centering bit disposed centrally within the cavity and having its point co-inciding approximately with the plane of truncation, and cutters carried by, and substantially co-inciding with the walls of the body and the cavity. 45

5. A cutter head comprising a truncated 50 conical body, and an inwardly inclined conical cavity extensive with the truncation.

6. A cutter head having a plurality of 55 conical surfaces, and cutters co-inciding substantially with the several surfaces.

7. A cutter head comprising a body having 60 reversely disposed substantially conical surfaces, and cutters substantially conforming with the surfaces.

8. A cutter head having a working face 65 formed by two reversely disposed co-axial, intersecting right cones.

9. A cutter head having a working face 70 formed by two truncated cones disposed co-axially with the base of one co-inciding with the perimeter of truncation of the other.

10. A cutter head comprising a truncated 75 conical body and a co-axial conical cavity, the base of which is co-extensive with the plane of truncation.

11. A rotary cutter head having blades 80 reversely inclined relative to the axis of rotation, and disposed to describe reversely disposed intersecting conical paths when the head is rotated.

12. A cutter head having a working face 85 formed as a surface of revolution with a co-axial re-entrant cavity.

In testimony whereof we affix our signatures.

EDWIN A. MCKOY.
GEORGE D. MOORE.
